[57] ABSTRACT

A conduit has an upper and a lower open end. A sealing ring surrounds the conduit exteriorly adjacent the lower open end, and a cover is mounted on the conduit to be located beneath the lower open end. The normally upwardly facing side of the cover is provided with a depression surrounded by an upstanding rim which is normally in engagement with the sealing ring. The depression is dimensioned to accommodate liquid entering through the upper open end, until the liquid reaches a certain level in the depression but below the lower open end of the conduit. A counterweight normally holds the cover in the position closing the lower open end of the conduit, but when the liquid reaches the aforementioned level the cover, which is pivotally mounted, pivots downwardly under the weight of the liquid in opposition to the counterweight, so that the lower open end of the conduit is opened and liquid which has accumulated in the depression of the cover is downwardly discharged.

CONDUIT CLOSURE

BACKGROUND OF THE INVENTION

The present invention relates generally to a conduit closure, and more particularly to a closure which permits entry of liquid into a conduit communicating with a reservoir, channel or the like, but prevents backing-up of the liquid out of the conduit.

Closures of the type here under discussion are used for various purposes, including for use with drainage conduits. For purposes of explanation the present invention will be discussed hereafter with respect to the use of the novel closure on a drainage conduit, although this should be understood to be exemplary only.

It is known to have a vertically oriented or near-vertically conduit section which has upper and lower open ends, with the lower open end communicating with a drainage or other conduit, reservoir or the like. 20 Mounted adjacent the lower open end, so as to normally close the same, is a cover whose purpose it is to prevent backing-up of the liquid out of the drainage conduit or reservoir with which the upright conduit communicates. A further purpose is to prevent gases or odors from escaping from the drainage conduit or reservoir into the surrounding atmosphere. On the other hand, the conduit must of course permit the entry of water or other liquid into the drainage conduit or reservoir. For this reason the cover is pivotally mounted so that as water accumulates in the upright conduit it will eventually overcome the force of a biasing means holding the cover in closed position, and will force the cover to move to open position so that the accumulated water can now run out of the upright conduit into the drainage conduit or reservoir. It is known from the prior art to provide a construction in which a sealing ring is located at the lower edge of the upright conduit, that is the edge face which faces in axial direction, and in which the cover itself is mounted for pivotal movement about a pivot axis which is located beneath the conduit itself, whereas a counterweight acting as a biasing means for the cover is located immediately laterally adjacent the conduit. In the closure position the general plane of the cover assumes a horizontal orientation, and the cover can turn to open position only through approximately 45°, because movement beyond this extent is prevented by the fact that the edge of the cover which moves upwardly during such movement contacts the upright conduit and is thus prevented from further movement. In this construction it is intended that there should always be some accumulated liquid remaining in a depression on the upper side of the cover, while the latter is in closure position, in order to provide a liquid seal between the cover and the upright conduit, a liquid seal which surrounds the sealing ring for the purpose of preventing the escape of undesirable odors.

This known construction has a number of disadvantages. One of these is the fact that when the maximum permissible liquid level in the depression of the cover is reached, the cover will not open spontaneously nor will it open to the fullest possible extent. It will open only relatively slowly and only as far as is necessary to permit the liquid to run out of the depression into the drainage conduit or reservoir. This means that if the flow of incoming liquid entering through the upper

open end of the upright conduit is relatively slow, the cover itself will open only to a small extent, and liquid will run out of the depression in the cover only slowly. The disadvantage of this is that the incoming liquid of course always brings with it contaminants, such as dirt, leaves or the like which, due to the fact that only a slow trickle of liquid escapes when the cover is open only to a small extent, will remain in the depression rather than being flushed out by a sudden dumping of the liquid.

10 These contaminants, moreover, eventually become lodged between the sealing ring and the cover, and then prevent proper sealing engagement between the two, defeating the purpose of the prior-art construction. Moreover, the contaminants frequently include rocks,

15 sticks and the like which tend to damage the sealing ring. Finally, the fact that the liquid is permitted to contact the sealing ring in this construction has the additional disadvantage that in wintertime the liquid tends to freeze on the sealing ring and the cover cannot turn at all, again defeating its intended purpose.

SUMMARY OF THE INVENTION

It is, accordingly, a general object of the present invention to overcome the disadvantages of the prior art.

25 More particularly it is an object of the present invention to provide a conduit closure of the type under discussion which is not possessed of these disadvantages.

30 Still more specifically the invention proposes to provide a conduit closure of the type in question which provides for a reliable trouble-free operation, and in which in wintertime the freezing-shut of the closure, in a sense preventing its intended operation, is precluded.

35 Another object of the invention is to provide such a closure which permits reliable and ready flushing of all or substantially all accumulated solid contaminants whenever the cover moves to open position.

40 In keeping with these objects, and others which will become apparent hereafter, one feature of the invention results in a structure of the character described herein, particularly a conduit closure for permitting the flow of liquid into but preventing the flow of liquid back out of a drainage conduit, comprising a conduit having spaced open ends and a mounting element for mounting the conduit in upright orientation so that the open ends constitute upper and lower ends, respectively. A sealing ring surrounds the conduit exteriorly

45 thereof adjacent the lower open end. A cover is mounted on the conduit so as to be located beneath the lower open end and has a major surface adapted to face the lower open end. The major surface is provided with a depression adapted to accommodate liquid entering through the upper open end until such liquid rises in the depression to a predetermined level below the lower open end. An upstanding rim bounds the depression. Mounting means mounts the cover for pivoting

50 movement between a position closing the lower open end and in which the rim sealingly engages the sealing ring, in a downwardly displaced position in which the cover opens the lower open end and liquid accumulated in the depression is discharged from the latter. Biasing means is connected with the cover and is operative for biasing the same to the closed position until accumulated liquid in the depression reaches the aforementioned predetermined level.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

BRIEF DESCRIPTION OF THE DRAWINGS

FIG. 1 is a somewhat diagrammatic vertical section illustrating an embodiment of the present invention, in closed condition;

FIG. 2 is a view similar to FIG. 1 but illustrating the same embodiment in open position; and

FIG. 3 is a section taken on line III—III of FIG. 1.

DESCRIPTION OF THE PREFERRED EMBODIMENTS

Discussing the drawing in detail it will be seen that reference numeral 1 identifies the conduit closure per se. It is mounted in a vertical shaft 2 of circular cross section with this shaft 2 constituting the entrance to a reservoir, a drainage conduit or the like. The inner circumference of the shaft 2 is provided with three abutments (there could be fewer or more) which are spaced in circumferential direction and designated with reference numeral 3, and which support a ring 4 which in turn supports the closure 1.

The closure 1 comprises a mounting element 5 of circular cross section, whose diameter corresponds to the internal diameter of the shaft 2 and which is provided at its underside with a circumferentially extending sealing ring 6 engaging the ring 4 and providing a seal therewith. An off-center rectangular inlet opening 7 is provided in the plate 5 and communicates with an upright conduit 8 which is fixedly connected with the plate or mounting element 5 and of the same cross section as the opening 7. The conduit 8 extends downwardly from the plate 5 and has, as illustrated in the drawing, an upper open end and a lower open end. The lower open end of the conduit 8 is designated with reference numeral 9 and above it a plate 10 is fixedly connected with the conduit 8 to extend in parallelism with the plate 5. Its cross section does not completely fill the cross section of the shaft 2, as FIG. 3 shows particularly clearly. The underside of the plate 10 is provided with two elements 11 which are spaced from one another and between which a shaft 12 extends in horizontal direction. A sleeve 13 is placed onto the shaft 12, so as to surround the same with play and carries at one side a plate 14 and at the diametrically opposite side a pair of arms 15 which carry between them a solid counterweight 16 of cylindrical cross section. Of course, the cross section could be different from what is illustrated. The purpose of the counterweight 16 is to urge the plate 14, which constitutes the cover, into the closed position shown in FIG. 1 in which the upper side of the plate or cover 14 sealingly engages a sealing ring 16a which surrounds the conduit 8 exteriorly of the same and somewhat upwardly spaced from the lower open end 9. The sealing ring 16a is mounted at the underside of the plate 10, as shown.

The cover 14 will be seen to be approximately shovel-shaped in its configuration, having a side which normally faces upwardly and which is provided with a depression 17 in which liquid entering through the upper

open end of the conduit 8 can accumulate. The drawing shows that the depression 17 is defined by a wall 18 adjacent the sleeve 13, a surface 19 which extends from the lower edge of the wall 18, and two triangular sidewalls 20, with the upper edges of these sidewalls being located in a common plane and forming an upstanding rim 21 which in the closed position of FIG. 1 engages the underside of the sealing ring 16a in sealing engagement therewith. In the illustrated embodiment the underside of the cover 14, that is beneath the surface 19 thereof, is provided with a sealed air chamber 22 which is bounded not only by the underside of the wall having the surface 19, but also by a surface 23 which extends from the lower edge of the wall 18, by a wall 24 and by two sidewall portions which constitute extensions of the sidewalls 20.

When enough liquid has accumulated in the depression 17 to overcome the biasing force exerted by the counterweight 16, the cover 14 pivots downwardly until it reaches a position in which the counterweight 16 abuts the conduit 8. In this position the cover has pivoted through approximately 90° out of its closed position in FIG. 1, and is located outside the flowstream of liquid which enters through the upper open end of the conduit 8. The counterweight 16 is essentially vertically above the shaft 12 at this point, and may even move slightly past the axis defined by the shaft 12. The force tending to return the cover 14 to the position of FIG. 1, that is the combined weight of the counterweight 16, the cover 14 and the arms 15, is rather small so that once the cover has moved to the open position it will remain there if even a small amount of liquid enters through the upper open end of the conduit 8.

With the exception of the sealing rings 6 and 16a, which may be of a suitable elastomeric sealing material such as natural or synthetic rubber, synthetic resin or the like, all other components of the construction may be made of synthetic plastic material, for instance polyethylene, nylon or the like. However, any or all of these components may be made totally or in part of metallic material if desired.

The construction according to the present invention requires little or no maintenance even over prolonged periods of time, and will operate reliably and without any difficulties even under varied and extreme operating conditions. Due to the fact that the sealing ring is located outside the path of liquid flowing through the conduit 8, or being discharged from the depression 17, damage to the sealing ring or freezing-shut of the construction is avoided. In many instances the incoming liquid carries with it certain chemicals which tend to attack the material of such a sealing ring, and this is of course also avoided in the construction according to the present invention where the sealing ring cannot be contacted by the liquid at all. Due to the fact that the lower end of the conduit 8 is so spaced from the cover 14 that it will not be immersed in the liquid accumulating in the depression 17, even at the time that the liquid has reached its upper level at which it will overcome the weight of the counterweight 16, freezing-shut of the construction is reliably precluded. Moreover, this arrangement also insures that even relatively large solid contaminants which have entered, such as relatively large stones or the like, can be discharged when the cover moves to the open position of FIG. 2, and that no solids can be retained which could become clamped between the cover 14 and the sealing ring 16a, or the

lower end of the conduit 8, and prevent the cover from operating as desired.

The cover according to the present invention will open not gradually but spontaneously once a level of liquid in the depression 17 has been reached at which the weight of the liquid overbalances the weight of the counterweight 16. This results in a sudden discharge of the accumulated liquid, and as a result in a proper clearing of any contaminants such as rocks, twigs, leaves or the like from the depression 17. Moreover, due to the fact that the relatively thin-walled upstanding rim of the cover contacts the sealing ring 16a, reliable sealing action is always assured, because the unit area pressure between the sealing ring 16a and the upstanding rim will be high due to the relatively small wall thickness of the same. This assures good sealing even if there is no flow of incoming liquid which could form a gas or odor seal in the depression 17.

The sealed air chamber could be omitted, but it is advantageous to provide it because this provides for an additional sealing effect if there is a back-up of liquid downwardly of the cover because such liquid then acts upon the cover, and the air entrapped in the sealed chamber has sufficient buoyancy to help urge the cover into even tighter sealing engagement with the sealing ring 16a. In fact, when the sealed air chamber is used it may in certain circumstances be possible to even omit the counterweight 16, namely in such circumstances where the construction is intended only to prevent backing-up of the liquid and when there is either no possibility that odors and gases might rise, or when their escape is not objectionable. In this case the cover would normally be in open position and would only be urged to sealing position when the liquid beneath it backs up.

When a sealed air chamber is provided, then it is advantageous if in a section substantially normal to its pivot axis the cover 14 is of approximately rectangular or trapezoidal hollow profile, having a diagonal wall which constitutes the upwardly inclined bottom of the depression and which separates the depression from the sealed air chamber. Such a construction is particularly simple to produce, and has the advantage that the air chamber with the buoyancy it can provide will be located relatively far from the pivot axis so that the lever arm in favor of the buoyancy factor is increased in an advantageous manner.

It is advantageous, but not necessary, if as shown in the drawing the cover 14, the pivot axis defined by the shaft 12 and the counterweight 16 are located substantially in a common horizontal plane when the cover is in the closed position shown in FIG. 1. The pivot axis is located outside the range of flow of liquid through the conduit 8 with such a construction, and the counterweight will produce its largest biasing force when the cover 14 is in closed position, whereas the biasing force will decrease as the cover begins to move towards open position, due to the decreasing lever arm of the biasing or counterweight, so that a spontaneous and rapid opening of the cover is thereby facilitated.

It is also advantageous if the cover can move through approximately 90° between the closure position of FIG. 1 and the open position of FIG. 2, although a different angle of displacement might be chosen. The 90° opening angle is, however, especially advantageous because a relatively light flow of liquid will maintain the cover in open position under these circumstances. The partic-

ular, essentially shovel-shaped construction of the cover 14 which has been illustrated in the drawing has certain advantages. The upwardly inclined surface bounding the depression 17, that is the inclination of the surface from the region of the pivot axis defined by the shaft 12 at one side of the conduit 8 towards the other side of the conduit 8 and the other side of the cover 14, assures that liquid which has accumulated in the deeper part of the depression 17 adjacent the edge where the pivot axis defined by the shaft 17 is located, will flow over the opposite edge which of course performs the greatest movement when the cover moves to open position. This provides for a particularly good flushing of accumulated solids from the depression as the liquid is dumped or discharged. In fact, as the cover begins to move to open position the liquid of course shifts towards this opposite side or edge, so that the effective lever arm of the accumulated liquid shifts in the same manner and the cover moves essentially spontaneously to open position, which facilitates the desired flushing-out of accumulated solids from the depression 17.

It will be understood that each of the elements described above, or two or more together, may also find a useful application in other types of constructions differing from the types described above.

While the invention has been illustrated and described as embodied in a conduit closure, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended:

1. A one-way closure for discharge conduits comprising, in combination, a mounting element connected to the discharge conduit interiorly thereof and subdividing the same in an upper and a lower compartment; an elongated connecting conduit sealingly connected to said mounting element and having an upper end portion communicating with said upper compartment, a lower end portion communicating with said lower compartment, and an internal surface partially bounding a liquid-flow path between said upper and lower compartments; a cover mounted in said lower compartment for pivoting movement with respect to said connecting conduit between a closed position and a fully open position; biasing means connected with said cover and operative for biasing the same to said closed position with a force gradually diminishing from a maximum force in said closed position to a minimum force in said open position; a depression provided in said cover and adapted to accommodate a predetermined quantity of liquid therein when said cover is in said closed position thereof so as to establish a maximum liquid level in said depression at which the weight of said predetermined quantity of liquid outbalances said maximum force with attendant rapid movement of said cover into said open

position thereof and discharge of said quantity of liquid; and a sealing ring arranged exteriorly of said lower end portion outside said fluid-flow path and above said predetermined level and sealingly engaging said cover when in said closed position thereof, whereby said compartments are sealingly separated as long as said cover is in the latter position, and the liquid is prevented from contacting said sealing ring.

2. A combination as defined in claim 1, wherein said biasing means comprises a counterweight.

3. A combination as defined in claim 2, comprising mounting means including a pivot member connected with said cover at one side of said connecting conduit, exteriorly of the latter.

4. A combination as defined in claim 3, wherein said mounting means defines a pivot axis; and wherein the configuration of said cover in a vertical cross-section extending substantially normal through said pivot axis is hollow and substantially rectangular.

5. A combination as defined in claim 3, wherein said mounting means defines a pivot axis; and wherein the configuration of said cover in a vertical cross-section extending substantially normal through said pivot axis

is hollow and substantially trapezoidal.

6. A combination as defined in claim 3, wherein said cover, pivot member and biasing means are located in a substantially horizontal plane common to them, when said cover is in said closed position.

7. A combination as defined in claim 3, wherein said mounting means mounts said cover for pivotal displacement through substantially 90°.

8. A combination as defined in claim 3, wherein said depression is partly defined by a major surface which is inclined in upward direction from said one to the opposite side of said connecting conduit when said cover is in said closed position.

9. A combination as defined in claim 1, said cover having a lower side which faces downwardly away from said lower end portion when said cover is in said closed position; and wherein said cover is provided with a sealed air chamber at said lower side.

10. A combination as defined in claim 1, wherein said sealing ring is upwardly spaced from a lower edge bounding said lower end portion of said connecting conduit.
